Atty.*

UNITED STATES PATENT OFFICE.

GEORGE W. PRENTICE, OF PROVIDENCE, RHODE ISLAND.

BUTTON-FASTENING.

SPECIFICATION forming part of Letters Patent No. 284,978, dated September 11, 1883.

Application filed July 5, 1883. (No model.)

To all whom it may concern:

Be it known that I, GEO. W. PRENTICE, a citizen of the United States, residing at Providence, in the county of Providence and 5 State of Rhode Island, have invented certain new and useful Improvements in Button-Fastenings; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My present invention relates to certain improvements in button-fastenings, and of the class which are adapted to be connected with or detached from fabrics at will without the use of a setting-instrument.

20 My invention consists, practically, of a fastener formed from a sheet-metal blank of T shape form and provided with a base or table which has an arm or wing extending from one side thereof, said wing being adapted to be 25 bent upward and back over the base to form a central spring-loop for retaining the shank of a button, and also further adapted to extend beyond the loop, thereby presenting a greater retaining-surface to the under side of 30 the fabric when attached thereto with button complete, all as will be more fully hereinafter set forth.

35 In the accompanying sheet of drawings, which illustrate my invention drawn enlarged, Figure 1 represents the sheet-metal blank from which the fastener is formed. Fig. 2 represents the fastener when connected to fabric with button, as it would appear in use. Fig. 3 represents a perspective view of the 40 fastener as provided with the extension loop or arm. Fig. 4 represents the same without such extension. Fig. 5 represents the latter fastener as connected to fabric with a button, as in use.

45 The following is a more detailed description of my invention and the manner of using the same:

A represents the fastener complete, consisting of the base or table A', from which extends, at right angles therewith, an arm or wing, A², terminating at a³. At a the base is indented or cut away, as shown in Fig. 1. The wing A² is adapted to be bent to form the spring-loop a⁴, the end a⁵ thereof extending beyond said loop, as fully shown in Figs. 2 and 3. I contemplate, however, reducing the length of said arm for certain connections, as shown at X, Fig. 1, and again shown in Figs. 4 and 5. I further propose making this same form of fastening from wire.

60 The manner of using my improved button-fastening is as follows: The fabric F has a slot, f, made therein, through which the shank b of the button B is inserted, after which the end a⁵ or x of the wing A² is passed through 65 said shank until the loop a⁴ arrives in proper position, when the button is now drawn upward until the base A bears against the under surface of the fabric, as shown, the end x of the loop springing into the notch a at the 70 same time.

I am enabled by this invention to furnish an efficient and inexpensive fastening, which is readily adapted for the rapid attaching of 75 buttons, and also adapted for detaching purposes.

Having thus described my invention, what I claim, and desire to secure by Letters Patent, is—

In a device for attaching buttons to fabrics, 80 the herein-described button-fastener A, consisting of the base-plate A', provided with the spring-loop a⁴, formed or bent directly over said base, and with the extension a⁵ and notch a, the whole arranged and adapted for 85 use substantially as shown and specified.

In testimony whereof I have affixed my signature in presence of two witnesses.

GEORGE W. PRENTICE.
